REAR SIGHT FOR RIFLES

Howard C. Cambridge, West View, Pa.

Application October 24, 1934, Serial No. 749,851

5 Claims. (Cl. 33—56)

This invention relates to sights for rifles and has particular reference to a rear sight especially adapted for use on "Krag" rifles.

At the present time the rear sight on rifles, and especially on the type of rifle above referred to, requires the elevation bar to be raised to its fullest height, or entirely removed from the base, in order to remove the bolt from the rifle, thereby altering the range setting of the elevation bar and making it necessary to reset the elevation bar after replacing the bolt.

An object of the present invention is to provide a sight whereby after the elevation bar has been properly adjusted for the proper range, the adjustment thereof need not be disturbed in order to remove the bolt from the rifle thus being a big improvement over the rifle sights as now used which require a rifleman to alter the elevation setting of his sight to remove the bolt, and upon replacing the bolt waste both time and ammunition in the re-sighting of his sight.

The invention, together with its objects and advantages will be best understood from a study of the following description taken in connection with the accompanying drawings wherein:

Figure 1 is a top plan view illustrating the application of the invention.

Figure 2 is a side elevational view of the invention.

Figures 3 and 7 are detail views taken substantially on the lines 3—3 and 7—7, respectively, of Figure 2.

Figure 4 is a perspective view of the elevation or range bar.

Figure 5 is a perspective view of a hinge block embodying the features of the present invention.

Figure 6 is a perspective view of a base member.

Referring to the drawings by reference numerals, it will be noted that the gun, a portion of which is shown fragmentarily in the drawings, is indicated by the reference numeral 10 while the bolt of the gun is indicated generally by the reference numeral 11. The sight which is mounted at the rear of the barrel of the gun is indicated generally by the reference numeral 12.

In accordance with the present invention, the sight 12 includes the usual elevation bar 13 which is slotted as at 14 and graduated as at 15. The sight member is indicated by the reference numeral 16 and the base thereof operates within the slot 14 for the transverse adjustment of the sight through the medium of the adjusting screw 17 in the usual manner.

In accordance with the present invention, the

sight includes a base plate 18 which is suitably apertured so that the plate may be secured to one side of the gun and the stock thereof, and at the rear end of the barrel in the usual manner and through the medium of screws or other fastening means 19. An important feature of the present invention is in providing the base plate 18 with a slot 20 in which works a hinge block 21 the same being provided with lateral vertical flanges 22 that engage the outer side 10 of the plate 18 when the parts are in the full line position shown in Figure 3. At its base the block 21 is hinged to the plate 18 at the lower or inner end of the slot 20 in any suitable manner and through the medium of a hinge pin 23. 15

In its outer face the block 21 is provided with a mortise groove 24 in which slidably fits the slide 25 that is formed integral with or otherwise secured to one end of the elevation plate 13. The plate 25 on its outer face is provided with the usual graduations for setting the range or elevation plate 13 at the desired range or elevation. For vertically adjusting the plate 13 there is provided the adjusting screw 26 that is threaded through the plate 13 and has its inner end operating in a suitable recess 27 provided therefor at the top of the block 21.

For releasably locking the block 21 in proper position, there is provided on the plate 18 at one side of the slot 20 a spring pressed plunger 30 30 28 that has an inner bevelled end adapted to engage in a recess 29 provided in one side of the block 21 to releasably lock the block 21 in position within the slot 20. The stem of the plunger 28 operates through a suitable plug 30 in the 35 outer end of the bore provided in the plate 18 for accommodating the plunger. The plug 30 is secured in position through the medium of a machine screw 31.

It will be apparent that when the sight is in 40 position on the gun and the proper adjustment of the elevation bar 13 and the sight 16 have been made, a removal of the bolt 11 can be easily effected by merely pulling outwardly on the plunger 28 to release the block 21 and subsequently to swing the block from the full line position to the dotted line position shown in Figure 3. With the block in the dotted line position shown in Figure 3 the bolt 11 may be readily withdrawn, and after replacement of the 45 bolt, the block 21 is swung from the dotted line position shown in Figure 3 to the full line position shown in said figure. Upon movement of the block 21 into the full line position, the plunger 28 will engage with the recess 29 in the 50 55

block for releasably retaining the block and associated parts in proper position. It will thus be seen that a movement of the block 21 and associated parts from one position to the other can be readily effected without disturbing the adjustment of the elevation plate 13 or the sight 16. Thus a removal and replacement of the bolt can be accomplished without loss of time, and waste of ammunition as would be occasioned 10 where the adjustment of the elevation plate would be required in order to permit a removal of the bolt.

Having thus described the invention, what is claimed as new is:

15 1. In combination with the elevation bar and base plate of a rear sight for rifles, a hinge block for the elevation bar hinged to the base plate on an axis longitudinal of the gun, and spring pressed plunger means carried by the 20 base plate and engageable with the block for locking the block in operative position relative to the base plate.

25 2. In combination with the elevation bar and base plate of a rear sight for rifles, a hinge block for the elevation bar hinged to the base plate, said hinge block being provided with a groove, a slide integral with the elevation bar and engaging in said groove, and means for adjusting said slide to the desired vertical position, said 30 hinge block, bar and slide being swingable laterally relative to the gun on an axis longitudinally of the latter.

35 3. In combination with the elevation bar and base plate of a rear sight for rifles, a hinge block for the elevation bar hinged to the base plate,

said hinge block being provided with a groove, a slide integral with the elevation bar and engaging in said groove, means for securing said slide at the desired vertical position, said hinge block, bar and slide being swingable laterally 5 relative to the gun on an axis longitudinally of the latter, and means on the base plate engageable with the block for releasably retaining the said block in operative position relative to the base plate. 10

4. In combination with the elevation bar and base plate of a rear sight for rifles, a hinge block for the elevation bar hinged to the base plate on an axis longitudinally of the gun, said hinge block being provided with a mortise groove, a 15 mortise slide integral with the elevation bar and slidably engaging said groove, and spring pressed plunger means carried by the base plate and engageable with the hinge block for locking the latter in operative position relative to the base 20 plate.

5. In combination with the elevation bar and base plate of a rear sight for rifles, a hinge block for the elevation bar hinged to the base plate on an axis longitudinally of the gun, a 25 slide mounted on said hinge block and engaged with the elevation bar for supporting the latter at the desired elevation, a sight member on said elevation bar and adjustable thereon-transversely of the gun, and a spring pressed locking element engaging the hinge block and the base plate for releasably securing the hinge block in operative position. 30
